UNITED STATES PATENT OFFICE.

PAUL MACGAHAN, OF PITTSBURGH, PENNSYLVANIA, ASSIGNOR TO WESTINGHOUSE ELECTRIC AND MANUFACTURING COMPANY, A CORPORATION OF PENNSYLVANIA.

RELAY.

1,227,469.

Specification of Letters Patent. Patented May 22, 1917.

Application filed June 11, 1915. Serial No. 33,489.

To all whom it may concern:

Be it known that I, PAUL MACGAHAN, a citizen of the United States, and a resident of Pittsburgh, in the county of Allegheny and State of Pennsylvania, have invented a new and useful Improvement in Relays, of which the following is a specification.

My invention relates to relays, and it has for its object to provide a relay having time-element characteristics.

In the accompanying drawings, Figure 1 is a diagrammatic view of a relay embodying my invention, and Figs. 2, 3 and 4 are diagrams illustrating time-element characteristics that may be obtained by a relay embodying my invention.

A circuit 1 is provided with a circuit interrupter 2 and a current transformer 3.

20 A relay 4 is provided for tripping the circuit interrupter 2 a time interval after the current that traverses the circuit 1 has increased to a predetermined value.

The relay 4 comprises two rotatable disks 25 or armature members 5 and 6, a magnetizable core member 7 for the armature 5, a main winding 8 and an auxiliary winding 9 for the magnetizable member 7 and permanent damping magnets 10 and 20 for the armatures 6 and 5, respectively. The shafts 11 and 12 of the respective armature members 5 and 6 are connected together by a spring 13. A movable contact member 14 is mounted upon the shaft 12 and adapted to engage 35 a stationary contact member 15. The contact members 14 and 15 constitute the separable terminals of a circuit 16 that comprises a battery 17 and the winding 18 of the tripping electromagnet 19 of the circuit interrupter 2. The winding 8 is connected to the secondary winding of the current transformer 3 for the purpose of actuating the armature 5 in accordance with the current traversing the circuit 1. While it

45 is here shown that the armature 5 is actuated in accordance with the current traversing the circuit 1, it will, of course, be understood that the windings 8 and 9 may be so variously connected that the armature 5 may be actuated either in accordance with the power traversing the circuit 1 or in accordance with any other electrical quantity.

50 The essential features of my invention are two movable members so resiliently connected together that one will operate sub-

stantially instantaneously, while the other may either operate after a lapse of a definite time interval or after a time that is inversely proportional to the current traversing the circuit. However, it will be understood that the armature 5 need not necessarily be provided with a damping magnet 20.

When a predetermined current traverses the circuit 1, the armature 5 rotates and, if the spring 13 is sufficiently strong, the armature 6 will also be rotated. Since the movement of the armature 6 is damped by the magnet 10, the whole system will rotate in a time that is inversely proportional to 70 the strength of the current traversing the circuit 1, to cause engagement of the contact members 14 and 15 and thus trip the circuit interrupter 2.

If the spring 13 is relatively weak and a 75 predetermined current traverses the circuit 1, the armature 5 will rotate substantially instantaneously but, because of the weakness of the spring 13 and the retarding effect of the magnet 10, the armature 6 will 80 require a definite time to complete its movement. Thus, after a lapse of a definite interval of time, the contact members 14 and 15 will be engaged to trip the circuit interrupter 2.

When the spring 13 is relatively strong, a characteristic curve, substantially as shown in Fig. 2, is obtained and, when the spring 13 is relatively weak, a characteristic curve, substantially as shown in Fig. 3, is 90 obtained. The spring 13 may be so proportioned that any combination of the two characteristics hereinbefore set forth may be secured substantially as shown by the curve in Fig. 4 wherein the device has a 95 substantially inverse time-element characteristic for relatively small overloads and a substantially definite time-element characteristic at other overloads.

It will be understood that the relay, as 100 here shown, is purely diagrammatic and that many modifications may be made therein without departing from the spirit and scope of my invention as set forth in the appended claims.

105 I claim as my invention:

1. A relay for an electric circuit comprising an actuated member, a retarded member and means connected therebetween whereby the retarded member is adapted to operate 110

in a time that varies substantially inversely as the current traversing the circuit up to a predetermined value of current and in a definite time for all values of current above the predetermined value.

5. A relay for an electric circuit comprising an actuated member, a retarded member and a resilient means connected therebetween whereby the retarded member is 10 adapted to operate in a time that varies substantially inversely as the current traversing the circuit up to a predetermined value of current and in a definite time for all values of current above the predetermined 15 value.

6. A relay for an electric circuit comprising an actuated member, a retarded member and a spring operatively connected therebetween whereby the retarded member is 20 adapted to operate in a time inversely as the current traversing the circuit up to a predetermined value of current and in a definite time for all values of current above the predetermined value.

7. A relay comprising a movable member, means for actuating the same, a retarded member and a spring operatively connected between the said movable and retarded members, said spring being so proportioned that it causes the retarded member 30 to be actuated in accordance with the movement of the movable member under predetermined conditions and to be actuated disproportionately to the movement of the 35 movable member under other conditions.

8. A relay for an electric circuit comprising a main and an auxiliary armature, means for actuating the main armature in accordance with the current traversing the 40 circuit, means for retarding the operation of the auxiliary armature and means for so

connecting the two armatures that the auxiliary armature is adapted to move in accordance with the main armature up to a predetermined value of current traversing the 45 circuit and to move with a substantially constant speed for all other values of current.

9. In a relay for an electric circuit, the combination with means actuated in accordance with the current traversing the circuit, 50 of a retarded contact device, and means for so connecting the said actuated means and the contact device that the contact device is adapted to close in a time that varies inversely proportional to the current traversing the circuit under predetermined conditions and to close in a definite time under other conditions.

10. In a relay for an electric circuit, the combination with means actuated in accordance with the current traversing the circuit, 60 of a contact device, and a spring for so connecting the actuating means and the contact device that the contact device is adapted to be actuated in accordance with the current 65 traversing the circuit under predetermined conditions and to have a definite time of operation under other conditions.

11. A relay comprising a movable member, means for actuating the same, a retarded 70 member and a spring operatively connected between the said movable and retarded members, said spring being so proportioned that it causes the retarded member to be actuated in accordance with the speed of the 75 movable member under predetermined conditions and to have a definite speed under other conditions.

In testimony whereof, I have hereunto subscribed my name this 27th day of May 80 1915.

PAUL MacGAHAN.
